Inventor

Morris Hausman

UNITED STATES PATENT OFFICE.

MORRIS HAUSMAN, OF SCRANTON, PENNSYLVANIA.

CLOTHESLINE.

Application filed October 5, 1922. Serial No. 592,592.

To all whom it may concern:

Be it known that I, MORRIS HAUSMAN, a citizen of the United States, residing at Scranton, in the county of Lackawanna and

5 State of Pennsylvania, have invented certain new and useful Improvements in a Clothesline, of which the following is a specification.

This invention relates to improvements in 10 clothes lines and has for its prime object to provide a clothes line at spaced intervals with a pivoted clamp for securing clothes on the line without the aid of the usual clothes pins.

15 A still further object of my invention is to provide a clothes line with spaced clamping members that are permanently carried by the line for instant use and which will eliminate the possibility of the clothes falling off of the line due to the old fashioned wooden clothes pins becoming disengaged from the line and clothes.

20 And a still further object of my invention is to provide a clothes line with spaced clamping members, that can be removed from the line when necessary, as would be the case should the line become rotten and unfit for further use due to elements of the weather.

25 And a still further object of my invention is to provide a clothes line of the above indicated character, which is simple in construction, durable, efficient for the purpose intended, and one that can be manufactured and placed on sale at a relatively low cost.

30 These and like objects of the invention will be better understood as the description follows and as is specifically pointed out in the appended claim.

35 Referring to the accompanying drawing which forms a part of this specification and which clearly illustrates the construction of my improved clothes line,

40 Figure 1 is a side elevation of a portion 45 of a clothes line constructed in accordance with my invention.

Figure 2 is a section taken on line 2—2 of Figure 1.

50 Figure 3 is an enlarged section of a portion of the clothes line, showing the means

employed for fastening the clamping members thereto.

Figure 4 is a section taken on line 4—4 of Figure 1, and

55 Figure 5 is a perspective view of one of the clamping members detached from the line.

Referring to the accompanying drawing in detail, like characters will be used to designate like parts in the different views. 60

In the drawing, the numeral 1 indicates a portion of a clothes line, which is constructed of twisted wire strands of the usual form.

Pivotedly mounted at spaced intervals on 65 the line 1 are clamping members 2 for firmly securing and holding clothes on the line 1 when same is in use. The clamping members 2 are so shaped as to conform to the curvature of the line 1, and are provided at one end with ears 3, the purpose 70 of which will be better understood as the description follows.

In order to mount the clamps 2 on the line for pivotal movement so that clothes 75 may be inserted between the clamps and the line, a metal ferrule 4 is inserted through the strands of the line 1 and a bolt or other fastening means 5 passes through openings 80 formed in the ears 3 and the metal ferrule 4, so that the clamping members 2 may freely move on the pivoted bolt 5.

In order to secure a frictional clamping action between the inner face 6 of the clamp 2 and the line 1, the outer walls of the 85 clamping member along each lower edge are provided with depressions 7 which form ridges 8 on the inner face 6.

In view of the foregoing description of my invention taken in connection with the 90 accompanying drawing, it is thought that any further explanation as to the construction, operation, and objects of this invention is unnecessary.

While I have shown and described the 95 preferred form of my invention, I realize that various minor changes may be resorted to, without departing from the spirit and scope of the invention as claimed, and therefore, I do not wish to limit myself to 100

the exact details of construction shown, nor to the combination and arrangement of parts.

What I claim as new and desire to secure 5 by Letters Patent is:

A clothes line provided at intervals along its length with a series of ferrules extending through said line and a series of clamping members each provided with a pivot in 10 one of said ferrules, said clamping members

being formed on their inner faces with a series of ridges for engagement with clothes on said line.

In testimony whereof, I have affixed my signature in the presence of two witnesses.

MORRIS HAUSMAN.

Witnesses:

Wm. D. WATROUS,
J. M. HAUSMAN.
